MATERIAL HANDLING DEVICE

William F. Anderson, Chicago, Ill., assignor to
 Fairbanks, Morse & Co., Chicago, Ill., a corpora-
 tion of Illinois

Application May 19, 1933, Serial No. 671,781

8 Claims. (Cl. 193—32)

This invention relates to material handling de-
 vices, and more particularly to an improved ma-
 terial delivery chute to be employed in connection
 with dispensing equipment for solid materials,
 5 such as a locomotive coaling station.

In certain of the older prevailing types of ma-
 terial handling apparatus, material is conveyed
 from a storage hopper to a receiving bin or hop-
 per, such as a locomotive tender, by means of a
 10 suitable delivery chute. The chute is usually
 pivotally mounted, particularly in locomotive
 coaling stations, so that the delivery end may be
 swung upwardly into an out of the way position,
 to clear any portion of the locomotive or train
 15 passing under it. A serious objection to the older
 prevailing forms of material delivery chute is the
 great danger of trapped material falling from the
 receiving end of the chute when the delivery end
 is raised into its inoperative position. It is, also,
 20 not an uncommon occurrence for the vibration,
 attendant upon swinging the chute to its inoper-
 ative position, to dislodge lumps of coal from
 the conveyor leading to the chute, the lumps fall-
 ing into the chute, and sliding out the rear end
 25 thereof, with likelihood of injury to workmen or
 others engaged about the base of the chute sup-
 port or tower.

Further objections to the older prevailing form
 30 of delivery or transfer chute, particularly the type
 of chute having a deflector member or hood on
 its delivery end, are the excessive noise produced
 by the lumps of coal striking the deflecting hood,
 and the resultant breakage of a part of the coal.
 35 The noise is particularly objectionable to pas-
 sengers on Pullman trains when coal is being de-
 livered to the locomotive tender during the night.
 Therefore, among the objects of the present in-
 vention is the provision of an improved silencing
 40 and cushioning element which may be located at
 the delivery end of a chute, and which is adapted
 to minimize the noise otherwise incident to the
 use of the chute, and to prevent breakage of the
 coal delivered to a locomotive tender, or other
 45 receiving bin.

Another object is to provide a safety device at
 the material-receiving end of the chute, which
 will effectively prevent any of the material, dis-
 loded by vibration or other cause, and falling
 50 into the chute when the chute is in its inoperative
 position, from being discharged at the rear end
 of the chute, with attendant hazards to per-
 sons and equipment.

A further object is to provide an improved
 55 gravity-actuated safety gate at the rearward end
 of the delivery chute, the gate being arranged to

close the rear end of the chute, when the chute is
 swung to its inoperative position.

A still further object is attained in the provi-
 sion of an improved flexible silencing and cushion-
 ing element, adapted to be hingedly secured in a
 suitable position within the deflector or hood
 member at the delivery end of the chute, the ele-
 10 ment being so arranged as to deaden effectively
 the impact of the descending material against
 the deflector, and to prevent in large measure,
 the breakage of the material.

Further objects and advantages will appear
 from the following specification, and from the
 drawing, in which:

Fig. 1 is an end elevation of a material con-
 15veyor system and the upper portion of a support-
 ing tower therefor, showing an improved delivery
 chute pivotally secured to the tower frame; Fig. 2
 is an enlarged sectional elevation of the de-
 20flector member or hood which is shown as at-
 tached to the discharge end of the chute, and
 showing a silencer cushion element therein, and
 the preferred manner in which it is swingably
 25 supported; Fig. 3 is a fragmentary sectional end
 view of the hood, and a sectional end view of the
 silencer cushion, and mounting therefor, as taken
 along line 3—3 in Fig. 2, and Fig. 4 is a sectional
 30 elevation of a rear end portion of the chute,
 showing a safety gate and the manner of support-
 ing it upon the chute.

Referring now to the drawing by numerals of
 reference, 10 designates, generally, a preferred
 form of material handling structure, including a
 supporting tower 12, which may be of any suit-
 able form and construction. In the present ex-
 35 ample, the description will refer particularly to
 a material handling structure intended for use
 in connection with locomotive coaling stations,
 hence the tower 12 will be mounted adjacent a
 railroad track (not shown). However, it is to
 40 be understood that the improved material han-
 dling equipment of the present invention may be
 applied to any purpose for which such apparatus
 is suitable.

Secured by any suitable means to an upper
 portion of the tower frame is a bracket structure
 45 14, having a portion thereof extending hori-
 zontally from the tower, as illustrated in Fig. 1. A
 material transfer conduit or chute 16 is pivotally
 secured, adjacent its material receiving end, to
 the extended portion of the bracket 14, the piv-
 50 otal connection being shown at 18. The pivotal
 connection permits the delivery end of the chute
 to be swung upwardly, so as to clear any portion
 of a locomotive or train passing thereunder.

The transfer member or chute 16 is preferably made of sheet metal, formed as a channeled or trough member having side walls 20 and a bottom 22. Secured to the under side of the upper end portion of the chute, and extending beyond the ends 26 of the walls 20, are balance or counterweight members 24 which render the chute easily movable about its pivot 18. The chute is usually moved about its pivot, from one position to another, by chains (not shown) connected to suitable points on the chute, the chains generally being controlled from an operator's shed (not shown) at the base of the tower.

A bucket type conveyor system, the upper end of which is shown at 28, extends to the top structure 30 of the tower 12 from a storage hopper (not shown), preferably located at the base of the tower. The buckets 31 convey material, coal in the present example, from the storage hopper 20 to a receiving hopper 32 secured to the structure 30 at the top of the tower. A coal opening or outlet 34 is disposed in a side of the hopper 32, adjacent the bottom thereof, and connects the hopper with the chute, when the chute is in its operative position, as shown in full lines, Fig. 1. It will be noted that when the chute is in operative position, the end portions 26 of the chute walls 20, as well as the chute bottom, overlap respectively the side walls and bottom of the hopper 32. The overlapping of these wall portions obviates any accidental loss of material at the point of connection between the hopper and chute.

A deflector or baffle member 36, including a material-directing wall 38 and side walls 40, preferably formed from sheet metal, is secured to the discharge end of the chute by rivets 42, or by any other suitable securing means. The wall 38, which in the present example is substantially vertical when the chute is in its material-delivering position, directs the material downward, and the side walls 40 coacting with the wall 38 to constitute a directing hood, aid in confining the material so that little or no material will be lost upon discharge from the end of the chute.

The excessive noise produced by the coal in striking the directing plate 38, has heretofore caused considerable annoyance to passengers on a train which has stopped to recoal the tender. The noise becomes particularly objectionable to sleepers on a Pullman train when the tender is being replenished late at night. Furthermore, a great amount of coal breakage occurs, since the coal lumps strike the baffle wall 38 with considerable force. Therefore, as a means for relieving these heretofore objectionable features of operation of the chute and deflector member, a flexible silencer or cushion member 44 is freely suspended, for swinging movement, between the walls 40 of the hood, and spaced somewhat rearwardly of the deflector wall 38. The cushion member is preferably composed of a leather or canvas base, coated on one or both sides with a layer of rubber, which may be vulcanized into or onto the canvas, the rubber covering resulting in a greater cushioning effect. In addition, the rubber layer on the canvas base, decreases the noise of impact between the coal and cushion member. The flap 44 is suspended from a supporting rod 46, secured between the walls 40 adjacent the upper edges thereof, preferably by a plurality of metal hangers or straps 48, the straps being looped over the rod 46 and secured to the cushion flap by rivets 50. The straps, however, may be formed from any suitable material, as

desired. The flap is weighted on its lower edge by a metal angle piece 52, secured thereto by any suitable means, such as rivets 54. As is readily seen in Fig. 1, the cushion member extends below the hood or deflector member, in order effectively to cover the hood lip portion 56, and to prevent any possible impact between the member 52 and lip 56.

A tail gate or closure member 58 is freely pivoted to the upper end of the chute, by a hinge or pivot pin 60, which extends through an enlarged apertured portion 61 of the gate, and has its ends bearinged in ears or lug portions 62 on the chute-balancing members 24. An arm 64, which may be made integral with the gate 58, extends downwardly from the point of pivotal support of the gate, and is disposed at an angle to the plane thereof. A weight 66 is secured to the free or outer end portion of the arm 64, for maintaining the arm vertical for any position of the chute within the limits of its pivotal movement. Since the gate and arm are rigidly connected, the gate will remain at a fixed angle with respect to the horizontal, in any position of the chute. Hence the gate, as illustrated, is essentially a gravity operated device. The angle between the gate and arm is such that the gate is parallel to the bottom of the hopper 32, when the chute is in its operating position, and tightly closes the rearmost end of the chute when the chute is in its inoperative position, as shown by dotted lines in Fig. 1. The purpose of the gate 58 is to prevent injury to workmen, immediately below the chute end, from falling pieces of coal which may have been dislodged from the bucket 31, by the vibration attendant upon swinging the chute to its inoperative position. Without the gate, a piece of coal becoming dislodged from the bucket 31 would drop into the hopper 32, roll out the aperture 34, and thence into the chute 16, whence it would escape from the rear end of the chute, and fall upon persons or objects below. Frequently, workmen about the base of the tower 12 have heretofore been struck and injured from such falling coal. The presently described safety gate 58 serves fully to obviate such danger. Since the weight 66 on the arm 64, is on the same side of the chute pivot 18 as the weight members 24, the weight 66 acts in conjunction with the weight arms 24 in counterbalancing the chute.

The element 44, freely suspended within the deflector member 36, functions as a cushion for the coal sliding down the chute, preventing breakage of the coal pieces, as they are deflected downward by the cushion and deflector wall 38. In addition, the element acts as a silencer, materially decreasing the noise otherwise due to impact of the sliding coal against the deflecting wall 38.

The safety gate and silencer cushion members, as applied to a chute of the type herein described, render the operation of the chute less objectionable as regards excessive noise, and adds to the safety of its use. Moreover, one or both of the members may be applied, as well, to other forms of chutes or material handling equipment.

It is to be understood, of course, that the present description of the elements of my invention are not limited to their illustrative forms, but may be altered or modified without departing from the spirit and full intended scope of the invention, as defined by the appended claims.

I claim:

1. In combination with material handling apparatus, a support, a material transfer chute pivotally associated with said support, said chute

having an inlet end and a discharge end, balance members adjacent the inlet end of said chute, and a gravity-actuated closure member pivotally secured to said balance members, and adapted upon the pivotal movement of the chute, to close the inlet thereof.

5 2. In combination with material handling apparatus, a conveyor and support therefor, a material-receiving hopper on said support having a discharge aperture in one side, a chute pivotally mounted on said support, and having an inlet formed by wall portions thereof, adapted over-lappingly to engage said hopper in relation to receive material through said discharge aperture, 10 counterweight members on said chute, and a gravity-actuated member pivotally secured to said weight members, and adapted upon swinging movement of said chute, to close said inlet.

15 3. In combination with a chute for coal and similar solid material, a pivot for said chute intermediate its ends, about which the chute is adapted to be swung between operative and inoperative positions, a tail gate for said chute, an arm secured to said chute and normally depending from the inlet end of the chute, and means coacting with said arm for swinging the gate into chute-closing position as the chute is swung about its pivot to an inoperative position.

20 4. In combination with material handling apparatus, a support, a material transfer chute pivotally mounted on said support, and having a discharge outlet at one end, a deflector member secured to, and extending beyond the discharge end of said chute, and a flexible member suspended within said deflector member for silencing and cushioning the flow of material from the discharge end of the chute.

25 5. In combination in material handling apparatus, a support, a material transfer chute pivotally mounted on said support, and provided with a discharge outlet at one end, an angular material deflector member secured to and extending beyond the discharge end of said chute, said member including a deflecting wall facing the discharge outlet of said chute, and a freely suspended flexible cushion member within said de-

flector member, spaced from said deflecting wall.

6. In combination in apparatus for handling solid materials, a support, a chute pivotally mounted on said support and having a discharge outlet at one end, a deflector secured to and extending beyond the discharge end of said chute, and including a deflecting wall facing the discharge outlet of said chute, a rod extending transversely of the deflector and spaced inwardly of said deflecting wall, a plurality of hangers on said rod, 10 and a flexible cushion member secured to said hangers, said flexible member being adapted to cushion the flow of material toward said deflecting wall.

7. A coal chute provided with a pivot intermediate its end about which the chute is adapted to be swung between its operative and inoperative positions, a pair of members swingably disposed at opposite ends of the chute, one of said members adapted as a gate to close one end of 20 the chute when the chute is in inoperative position, a counterweight for closing and opening said gate as the chute is moved, the other of said members adapted as a baffle and mounted for swinging movement under the impact of a stream 25 of material through said chute.

8. In combination in apparatus for handling solid materials, a conveyor and a support therefor, a material-receiving hopper on said support adapted to be supplied from said conveyor, a chute 30 pivotally mounted on said support, having an inlet end formed to engage said hopper in one position of pivotal chute movement; said chute having a discharge end and a material-deflecting hood secured thereto, said hood including a deflecting wall facing said discharge end, a flexible cushioning member freely suspended within said hood, and spaced inwardly of said deflecting wall, and adapted to cushion the impact incident to flow of material toward the deflecting wall; 40 counterweight members carried by the inlet end of said chute, and a gate, pivotally mounted on said weight members, and means coacting with the gate, upon pivotal movement of said chute, to close the inlet end of said chute. 45

WILLIAM F. ANDERSON.
